UNITED STATES PATENT OFFICE.

FRED M. OEDER AND JAMES E. WRIGHT, OF WEST BAY CITY, MICHIGAN.

BEET-THINNING SHOE FOR CULTIVATORS.

SPECIFICATION forming part of Letters Patent No. 639,275, dated December 19, 1899.

Application filed April 12, 1899. Serial No. 712,767. (No model.)

To all whom it may concern:

Be it known that we, FRED M. OEDER and JAMES E. WRIGHT, citizens of the United States, residing at West Bay City, in the county 5 of Bay and State of Michigan, have invented certain new and useful Improvements in Sugar-Beet-Thinning Shoes for Cultivators; and we do hereby declare the following to be a full, clear, and exact description of the invention, such as will enable others skilled in the art to which it appertains to make and use the same.

Our invention relates to machines for thinning sugar-beets—that is, removing the 15 plus young beets from the row in which they were planted and leaving only the best and most promising beets at regular intervals in the rows; and our improvement pertains more particularly to the construction of the cutting 20 knives or shoes by which the thinning operation is accomplished.

The objects of our invention are, first, to provide a pair of beet-thinning shoes that can be readily attached to existing forms of hand-cultivators; second, to produce a pair of thinning-shoes that can be adjusted vertically to suit the height of the operator for convenient handling and that can be brought together or separated to suit different sizes of beets or 30 tilted up in front to cut the crust of earth that forms on lowland beet-fields; third, to provide shoes that will not obstruct the view of the beet while the shoe is being set over it preparatory to removing the neighboring beets; fourth, to provide a pair of shoes that can be adjusted to turn in at the forward end and separated at the rear end to prevent injury to the young plants by a sudden side-wise movement of the cultivator-frame when 40 it is pushed forward, as is frequently the case when one of the cultivator-wheels encounters an obstruction or a hole in the ground; fifth, to produce as an article of manufacture a sugar-beet-thinning shoe made of a single 45 piece of metal that shall be inexpensive to make and thoroughly efficient in its operation.

Our invention is illustrated in the accompanying drawings, throughout the several 50 views of which similar figures of reference are used to designate similar parts and devices.

In the drawings, Figure 1 is a view in per-

spective of a machine embodying our improvement. Fig. 2 is a top view of a pair of the beet-thinning shoes, showing the method of attachment to the frame of the machine. Fig. 3 is a front view of a pair of shoes attached to the frame. Fig. 4 is a view in perspective of a single shoe and its attachment.

As is clearly shown in the drawings, each 60 of the pair of shoes that together make up our improvement consists of a side or body portion 1 and a rearwardly and downwardly extending wing portion 2, both of which are preferably made from a single piece of sheet 65 metal.

In practice the shoes are used in pairs, one right hand and one left hand, and separated from each other, so as to permit the shoes to be placed one on each side of the beet that is 70 to be saved, when by a forward movement of the machine-frame the shoes are advanced and the lower cutting edges of the wings 2 cut off and carry aside the surplus plants on either side of the remaining beet.

The forward sloping edge 1^a of the side 1 is rounded on the top, so as to pass under and raise the leaves of the larger beets without injuring them. The sides 1 are slanted away from the vertical from the bottom up, thus 80 permitting the operator to see the bottom or cutting edges of the plate 1 by looking between the shoes and enabling him to easily locate the shoes, so as to operate without injuring the beet he wishes to save. By sloping the wings 2 outwardly and downwardly, as shown in the drawings, the severed beet-leaves are not left between the remaining rows of beets, but are pushed aside, leaving 85 the soil around the beets free and affording 90 better opportunity to inspect them and keep them in proper growing condition.

At the top edge of the side 1 is provided a projection 1^b, preferably attached by rivets or otherwise to the side 1 or made integral 95 with it, as shown in the drawings, and having a hole 3, adapted to receive a bolt 3^a for clamping a bracket 4 to the shoe. The bracket has a vertical slot 4^a, through which the bolt 3^a passes, by means of which vertical 100 adjustment of the shoe may be accomplished, and also allowing the toe of the shoe to be raised or lowered. By tilting the shoe so as to raise the toe 5 clear of the ground the rear

part of the cutting edge 1^b is made to cut the soil at the side of the beet with a shearing movement, while the lower cutting edge of the wing 2 severs the adjacent beet-tops and weeds and carries them to one side. The means for tilting the shoe, as above described, produces important practical results, for in practice it is found that a thin crust or shell of hard earth forms over a beet-field, especially 10 in low localities, and cultivators having teeth with flat horizontal cutting edges or sharp downwardly-extending parts catch under the crust and by disturbing it uproot the young plants, causing great loss. Cutting the soil 15 with a shearing action, as is done by our improved shoe when tilted up in front, as above described, overcomes this difficulty and preserves the plants.

The top of the bracket 4 has a horizontal 20 flange and is bolted through its top portion to the frame 6 of the cultivator mechanism. By adjusting the bolt 7 horizontally in the slot usually provided in such machines the distance between the cutting edges of the 25 shoes can be increased or diminished to suit the varying sizes of the beets, increasing as the growing season advances. A fourth advantage of the horizontal flange on the bracket 4, with its adjusting-bolt 7, is that the 30 shoes may be swerved horizontally, so as to bring the toes of the shoes closer together and separating the after parts. Thus in uneven or stony ground or soil having many irregularities in its surface when the shoes are thus 35 swerved, as is shown in Fig. 2, the points can be easily placed each side of the beet, and when the machine is pushed forward if the wheels encounter a hole or other obstacle the sidewise jerk of the frame incident thereto 40 will be less liable to cause the cutting edges 1^b to injure the beet.

It is thus seen that by the means above described we produce an attachment for hand cultivator-machines that is simple in construction and efficient in practice, that can be 45 manufactured at small cost, and that will take the place of the larger part of the hand-work heretofore employed in the beet-fields.

What we claim as our invention, and desire to secure by Letters Patent, is—

1. In a beet-thinning device for attachment to cultivators, the combination with a downwardly-projecting horizontally-adjustable bracket attached to the cultivator-frame and having a vertical slot; of a cutting-shoe comprising a side portion sloping downwardly and inwardly and having a lower horizontal cutting edge and an upwardly and rearwardly extending blunt forward edge, and a wing portion formed integral with the side portion 60 and extending outwardly and downwardly from the rear part thereof and having a lower horizontal cutting edge, said shoe being adjustably attached to said bracket, substantially as set forth. 65

2. A beet-thinning shoe made of a single piece of sheet metal comprising a downwardly and inwardly inclined side portion having a cutting bottom edge and an upwardly and rearwardly extending non-cutting forward 70 edge; a downwardly and outwardly extending wing portion formed by diagonally flanging the sheet metal from the side portion, said wing portion having a cutting bottom edge; substantially as described. 75

In testimony whereof we affix our signatures in presence of two witnesses.

FRED M. OEDER.
JAMES E. WRIGHT.
